UNITED STATES PATENT OFFICE.

FRANK O. WALThER, OF NEW YORK, N. Y., ASSIGNOR TO WALThER & COMPANY, OF NEW YORK, N. Y., A FIRM.

DESIGN FOR WRAPPING-PAPER.

No. 37,775.

Specification for Design.

Patented Jan. 2, 1906.

Application filed October 19, 1905. Serial No. 283,551. Term of patent 14 years.

To all whom it may concern:

Be it known that I, FRANK O. WALThER, a citizen of the United States of America, and a resident of the borough of Manhattan, in the county of New York, city of New York, and State of New York, have invented a new, original, and ornamental Design for Wrapping-Paper, of which the following is a specification, reference being had to the accompanying drawing, forming part thereof.

The figure shows the design.

The paper has repeats of the design comprised within the boundary line.

I claim—

The ornamental design for wrapping-paper, as shown.

FRANK O. WALThER.
